United States Patent Office

Des. 187,592
Patented Apr. 5, 1960

187,592

COMBINED TELEPHONE STAND AND AMPLIFIER

Francis H. Lehman, New Rochelle, N.Y.

Application June 19, 1959, Serial No. 56,434

Term of patent 14 years

(Cl. D26—14)

Fig. 1.

Fig. 2.

Fig. 3.

Fig. 1 is a perspective view of a combined telephone stand and amplifier, showing my new design, the broken line showing of an associated loud speaker and connecting cord being for illustrative purposes only;

Fig. 2 is an end elevational view on enlarged scale; and

Fig. 3 is a top plan view thereof on enlarged scale.

I claim:

The ornamental design for a combine telephone stand and amplifier substantially as shown and described.
